UNITED STATES PATENT OFFICE.

FREDERICK C. LAUTZ, OF VAUXHALL, NEW JERSEY, ASSIGNOR TO DAVID BELAIS, INC., OF NEW YORK, N. Y., A CORPORATION OF DELAWARE.

DESIGN FOR A FINGER RING OR SIMILAR ARTICLE.

Application filed March 29, 1923. Serial No. 5,630. Term of patent 3½ years.

To all whom it may concern:

Be it known that I, FREDERICK C. LAUTZ, a citizen of the United States of America, and resident of the city of Vauxhall, county of Union, State of New Jersey, have invented a new, original, and ornamental Design for a Finger Ring or Similar Article, of which the following is a specification, reference being had to the accompanying drawing, forming part thereof.

I claim:

The ornamental design for a finger ring or similar article, as shown.

FREDERICK C. LAUTZ.
